UNITED STATES PATENT OFFICE.

CLARENCE E. McHUGH AND JOSEPH A. KOMODOWSKI, OF MANKATO, MINNESOTA.

SHOE AND PROCESS OF MAKING THE SAME.

Application filed October 29, 1925. Serial No. 65,607.

Our invention relates to an improved shoe and process of making the same. The invention is directed particularly to an improvement of the heel structure of the heel portion of the shoe, whereby, without the use of nails, the shoe heels are very securely anchored to the shoes, and even very high heels, such as French heels, used on ladies' shoes will be securely held and prevented from turning over or becoming loose. The salient feature of the invention is found in the use of an anchoring plate that is securely incorporated in the heel structure of the shoe, in a novel way, and is provided with rivets extended into or through the outer sole and preferably deep into the heel, thereby reinforcing the heel and rigidly securing the same to the anchoring plate and through the anchoring plate to the shoes. This invention will be made clear from the description of the accompanying drawings, wherein like characters indicate like parts throughout the several views.

Referring to the drawings:

Fig. 1 is a fragmentary perspective showing the first step in the process of carrying out our invention;

Fig. 2 is a fragmentary perspective showing the second step of the process;

Fig. 2^a is a fragmentary perspective illustrating a minor feature of the second step of the process;

Fig. 3 is a fragmentary perspective illustrating the third step of the process;

Fig. 4 is a plan view with some parts broken away, illustrating the fifth step of the process;

Fig. 5 is a section on the line 5—5 of Fig. 4;

Fig. 6 is a longitudinal section of the shoe, some parts being broken away but illustrating the completed heel or rear portion of the shoe; and

Fig. 7 is a plan view illustrating a modified form of the anchoring plate.

Of the parts of the shoe, the numeral 9 indicates the shoe lining, 10 the inner sole, 15 the shoe "counter", 16 the shoe upper, 20 the outer sole, and 21 the leather heel-forming layers, said heel, as shown, being provided with a ground-engaging supplemental section 22. Preferably and as customary, the lining 9, counter 15 and shoe upper 16 will be stitched together at their heel-engaging edges.

The numeral 11 indicates an anchoring

plate preferably of thin sheet metal provided with a tongue or extended portion 12. In the form of anchor plate best shown in Figs. 1 and 2, the said member is provided with large marginal thread or needle passages 13, but in the modified form shown in Fig. 7, said anchoring plate is made of slightly smaller marginal dimension and the said marginal passages are omitted. These anchoring plates, while preferably made of metal, may be made of any thin and quite stiff material, such as vulcanized wood fibre or the like.

The first step in the process of assembling the above described parts of the shoe consists in placing the anchoring plate 11 on top of the inverted inner sole 10 with its rivets 14 projecting upward and with its tongue 12 extending over the instep portion of the sole, as shown in Fig. 1.

The second step consists in placing the edges of the three shoe elements 9, 15 and 16 over the thread or needle passages 13, as shown in Fig. 2, and then lacing the said edges together by basting threads 17, as shown in Fig. 2^a.

The third step of the process consists in applying the outer sole 20 against the inner sole and inturned flaps of the elements 9, 15 and 16, and in passing the rivets 14 through perforations provided therefor in the said outer sole, as shown in Fig. 3.

The fourth step of the process consists in applying the stitches 18 through the outer sole, inner sole, inturned flaps of the elements 9, 15 and 16 and through the needle passages 13 of the anchoring plate 12. If the anchoring plate shown in Fig. 7 be used, then the stitches 18 will be passed, not actually through but very close to the edge of said anchoring plate, but in either event, the anchoring plate will be very firmly clamped and secured between the two soles of the shoe and its rivets will project through the outer sole for engagement with the shoe heel. In Fig. 5, the inner sole 10 is provided with a skive-forming flap 19 that may be turned up for stitching and then pressed down and secured by cement. However, this feature of employing the skive and flat is not absolutely necessary.

The fifth step in the process consists in applying the heel-forming sections, as shown in Fig. 6, with the rivets 14 extended through more or less of the said heel sections. Said heel sections will, of course, be formed with

perforations of a size to permit the rivets 14 to be quite freely passed therethrough. The rubber section 22 in the heel shown will be applied after the rivets have been passed through the heel sections 21 and upset or expanded at their ends.

The form of anchoring plate shown in Fig. 7 is best adapted for use in machine work, because of the difficulty of making 10 the machine needle register with the needle passages of the plate shown in the other views.

As is evident, the heel applied as above described will be very securely anchored 15 and will be caused to keep its form and the necessity for nails is eliminated. The bond between the heel proper and the outer sole is very securely made by the rivets 14, and as the anchoring plate 11 or 20 11^a, as the case may be, is in itself very securely anchored to the inner sole by the stitches 18, the entire heel will be very firmly anchored in the shoe structure. Even 25 high heels, such as French heels, and some of which are made of wood, will be reinforced and securely anchored both to the inner and outer soles, so that there is no danger of the same being broken off or tilted out of position.

30 The resilient tongue of the anchoring plate reinforces the shoe sole at the instep and it will be understood that the force that bends this tongue portion in walking will be transmitted through the anchoring plate to 35 the rivets and, hence, to the heel.

Of course, it will be understood that the

preferred form of invention herein described is capable of modification within the scope of the invention as herein set forth and claimed.

40

What we claim is:

1. The process of making shoes which consists first in applying an anchoring plate to the inner sole heel, second in overlapping by inturned edges of the elements 45 of the shoe upper the edge of said anchoring plate, third in applying the outer sole to the inturned edges of the said shoe upper, fourth in stitching said assembled elements together along the edge of said anchoring 50 plate, and fifth in securing the heel to said outer sole and to said anchoring plate.

2. The process of making shoes which consists first in applying to the inner sole heel an anchoring plate having projecting 55 rivets outturned therefrom, second in overlapping by inturned edges of the elements of the shoe upper the edge of said anchoring plate, third in applying the outer sole to the inner sole and to the inturned edges 60 of said shoe upper with the rivets passed through perforations in said outer sole, fourth in stitching said assembled elements together along the edge of said anchoring plate, and fifth in securing the heel to the 65 outer sole with the rivets extended into the same.

In testimony whereof we affix our signatures.

CLARENCE E. McHUGH.
JOSEPH A. KOMODOWSKI.
